DIE ASSEMBLY FOR COMBINED FEEDING
AND COLD DRAWING MECHANISM

Lee Berkebil, Detroit, Mich., assignor to B. W. Manufacturing Company, Detroit, Mich., a corporation of Michigan

Original application June 27, 1938, Serial No. 216,134. Divided and this application March 25, 1939, Serial No. 264,250

34 Claims. (Cl. 205—3)

This invention relates generally to combined feeding and cold drawing mechanism for heading machines and constitutes a division of my application filed June 27, 1938, bearing Serial No. 5 216,134.

One of the essential objects of the invention is to provide a machine of this type with an improved die assembly wherein the die proper is mounted to permit longitudinal movement there- 10 of against frictional resistance to compensate for any backward movement of the stock caused by the action of a gauge stop to obtain an exactly measured length to be sheared.

Another object is to provide a die assembly 15 wherein the movable die is provided with a yieldable shoe to obtain the frictional resistance desired.

Another object is to provide a die assembly 20 wherein provision is made for varying the tension on the frictional shoe.

Another object is to provide a die assembly 25 wherein provision is made for limiting the longitudinal movement of the die as required.

Other objects, advantages and novel details of 30 construction of this invention will be made more apparent as this description proceeds, especially when considered in connection with the accompanying drawings, wherein:

Figure 1 is a sectional plan view of a heading 35 machine to which my improvements are applied;

Figure 2 is a side elevation of the feeding mechanism;

Figure 3 is a vertical central longitudinal section therethrough;

Figure 4 is an enlarged vertical longitudinal section on line 4—4 of Figure 1;

Figure 5 is a similar view showing the parts in a different position of adjustment;

Figure 6 is an enlarged horizontal section 40 through the sizing die on line 6—6 of Figure 2;

Figures 7 and 8 are end elevations of the cut-off and transfer means for the blank;

Figure 9 is a section on line 9—9 of Figure 8 showing the heading mechanism;

Figures 10, 11 and 12 are similar views illustrating successive steps in the heading operation;

Figures 13 and 14 are diagrams illustrating the operating and timing mechanism;

50 Referring now to the drawings, A is the bed or frame and B a reciprocating head slidably engaging ways C and actuated by a crank or eccentric D on the main driving shaft E, through the medium of a connecting rod F. On the head 55 B is mounted a vertically reciprocating slide B'

which carries a plurality of heading dies B², B³. The stock for forming the blanks is advanced in a plane laterally offset from the plane of the dies B², B³. It is then cut off in predetermined lengths and the blanks thus formed are transferred into the plane of the dies to be successively operated upon thereby. The mechanism for accomplishing these functions includes a gear wheel G on the shaft E which drives an intermeshing gear wheel G' in a 1 to 2 ratio. The 10 gear wheel G' is upon a shaft G² which extends transversely of the bed parallel to the shaft E. At opposite ends of the shaft G² are variable throw cranks G³ and G⁴; the one for operating the stock feeding mechanism, and the other for 15 operating the blank shearing and transfer mechanism. There is also a cam G⁵ on the shaft G² which operates a mechanism for actuating the slide B' so as to alternately place the dies B² and B³ in registration with a cut-off blank in its 20 transferred position. More in detail and as shown in Figure 13, the crank G³ is provided with a crank pin H, which is adjustable radially in a slot H' to increase or diminish the throw thereof. A rod H² connects this crank pin with an 25 adjustable pin H³ on the lever H⁴ for oscillating a gear wheel I, the arrangement being such that for two revolutions of the crankshaft E one revolution is imparted to the crank G³. Also, the length of the arc through which the gear wheel 30 I is oscillated may be varied by adjustment of the crank pins H and H³. This gear wheel forms a part of my improved stock feeding and drawing mechanism which will be hereinafter described.

The crank G⁴ is connected by a rod J with a 35 slide J' which has a cam slot J² engaging a pin J³ on a transversely movable slide J⁴. The slide J⁴ actuates the shearing and transfer member J⁵ as will be later described.

The mechanism for operating the slide B' is 40 shown in Figure 14 and comprises a slotted member K slidably mounted on a bearing K' on the shaft G² and reciprocated by the cam G⁵ which engages rollers K² on the member K. Preferably, this member K is connected to a rock arm K³ 45 on a rockshaft K⁴, which extends transversely of the bed and has a rock arm K⁵ connecting the same with slide B'. The cam G⁵ is so fashioned as to intermittently actuate this mechanism to raise and lower the slide B' with a dwell at each 50 end of the movement thereof.

Connected to the bed A and arranged in a vertical plane which is radially offset from the plane of the dies B², B³ is a frame L. This frame is formed in several sections including a central 55

die-holding section L' and sections L² and L³ on opposite sides thereof which constitute slideways for stock feeders. The outer end of the frame is also floatingly supported by a pivotal link member L⁴ which rises from a supporting base L⁵. The stock is advanced through the frame L in a direction from left to right, Figures 1 to 3, and for convenience in description I will designate the portion to the right as forward and that to the left as rear.

Extending across the bed A and the forward end of the frame L are a pair of shafts M and M' which are in the same vertical plane and are connected to each other at one end by the intermeshing gear wheels I and I' fixed to the respective shafts. In central alignment with the frame L are rock arms M² which are connected by links M³ with a sliding head N forming the forward feeder.

20 The slide head N of the forward feeder has spaced upper and lower portions forming wedge surfaces N' which taper from forward to rear. These portions are held in rigid relation to each other by side plates N² and suitable splines 25 (not shown). Clamping jaws N⁴ are within the recess and have their outer surfaces parallel to the surfaces N' with rollers N⁵ arranged therebetween. The jaws N⁴ embrace the stock which is to be fed and during the forward movement 30 of the head N the resistance or load will tend to draw the jaws rearward, thereby wedging the same to tightly grip the stock. On the other hand, when the member N is moved rearward, this will instantaneously release pressure on the jaws so as to permit the same to slide rearward 35 over the stock. Springs N⁶ within the recess and bearing against the forward ends of the jaws will hold the same in frictional engagement with the stock. There are also bushings N⁷ and N⁸ in the sliding head N for guiding the stock passing 40 therethrough.

The intermediate section L' holds the die member O through which the stock is passed to slightly reduce the diameter and finish the surface thereof. This die member, as shown in Figure 6, is mounted to permit a slight longitudinal movement thereof against frictional resistance. For this purpose the die is surrounded by an annular member O' which is fixed in the forward wall O² of the section L'. A friction shoe O³ extending through a recess in the annular member I' bears against the die O, and a spring O⁴ places a tension on the shoe. This tension may be varied by an adjusting screw O⁵ which 45 bears against the follower O⁶ forming an abutment for the spring. To limit the sliding movement of the die within the annular member O' screws O⁷ extend through threaded apertures 50 in the rear wall O⁸ of the section L' into proximity to the die, and these screws may be adjusted to obtain the desired amount of movement.

Inasmuch as the feeder N is forward of the die O it is obvious that some additional means 55 must be provided to advance the forward end of the stock through the die before it can be engaged by said feeder. For this purpose I have provided a second feeder P which is substantially the same in construction as the feeder N and, 60 therefore, will not be described in detail. This second feeder is actuated by the feeder N through the medium of rods P'. When thrown into operation the feeder P may be used for advancing the stock through the die O and into engagement with the forward feeder N.

The bushings N⁹ and N¹⁰ for the feeder N may be selected with respect to the diameter of stock to be passed therethrough and similar bushings are provided for the feeder P which are of a diameter corresponding to that of the 5 stock before it passes through the sizing die O. Still another bushing S is mounted at the rear end of the frame L and the stock is first fed through this bushing and into operative relation to the jaws of the rear feeder P.

In the operation of the machine the feeding mechanism may be adjusted to advance the stock bar during each forward movement an amount slightly greater than the length of blank which is desired. The stock bar is then moved 15 slightly rearward so that the length actually sheared therefrom is exactly as predetermined. However, during the shearing operation the shear blade must be inserted between the severed blank and the remainder of the stock and as the shearing member cannot itself move rearward, it necessarily forces the severed blank 20 slightly forward.

Heretofore, machines of this kind have been provided with stops which, during the shearing movement, are rigid and hold the forward end 25 of the sheared blank from any displacement. Such construction is objectionable in not providing for the displacement of the blank during shearing and I have therefore designed an improved construction. This, as shown in Figure 30 1, comprises a resilient member U secured to an adjustable screw U' and projecting laterally therefrom into the path of the stock bar. The screw U' may be adjusted so that the stop is in 35 advance of the shearing plane a distance corresponding to the required length of blank. Consequently, as the stock bar is severed a certain amount, it will impinge against this resilient stop and slightly displace it in a forward direction. However, upon the rearward movement of the feeder N the resiliency of the member U will force the stock bar rearward which is 40 permitted by the freedom of the die O to slide rearward in the annular member O'. To insure a positive action independent of the resiliency of the member U, a stock member U² 45 on the slide B' is moved against said member U during alternate rearward movements of the head B. However, before the shearing of the 50 blank takes place, the positive stop is withdrawn which permits the flexible stop member U to be deflected forward the required amount.

In operation, the stock which is preferably hot-rolled and coiled is placed in a suitable 55 holder, not shown, and its forward end is passed through the bushing S into engagement with the rear feeder P. After the required number of reciprocations of the feeder P, the stock bar will be advanced into engagement with the die O and then forced through the latter. The forward advancement by the rear feeder is continued until the forward end of the stock bar which has been sized by the die O comes into operative engagement with forward feeder N. 65

When the forward end of the stock passes beyond the shearing plane the projecting portion will be cut off and in succeeding operations predetermined lengths will be advanced in each operation. The length of advancement is determined by the adjustment of one or the other of the crank pins H and H³ to increase or diminish the amplitude of oscillation of the shafts M and M'. This length may be, however, somewhat in excess of the length desired for the blank so that 70 75

the forward end will impinge against the resilient stop U and slightly displace the same. As soon as the feeder N begins its return movement the resiliency of the stop will push the stock rearward carrying with it the die O which slides in the annular member O'. When the construction shown in Figure 1 is used the stop U² on the slide B' will be brought in contact with the resilient stop U to insure a full return movement of the latter to its normal position. Thus, the length of blank projecting beyond the shearing plane is predetermined.

The operations of shearing the blank, transferring it into the plane of the heading dies and alternate shifting of these dies into alignment with the blank, are accomplished by the mechanism described. In brief, the movement of the slide J' by the crank G⁴ will through its cam slot J² move the transverse slide J⁴ and shear member J⁵. This shear member has mounted thereon a resilient clip V which holds the sheared blank to the shear member and carries with it into the plane of the dies B² and B³, as shown in Figures 7 and 8. The shape of the cam slot J² is such as to produce a dwell of the shear member when the blank is in the plane of the dies, and by reason of the 1 to 2 ratio of the gears G and G', there will be two reciprocations of the head B to one reciprocation of the transfer member J⁵. Also, between reciprocations of the head B the mechanism shown in Figure 14 will operate to move the slide B' so that during one reciprocation the die B² is registered with the blank and during the other, the die B³. A co-operating stationary die B⁴ is in registration with the blank in its transferred position. After the initial movement of the die B² sufficient to engage the same with the blank the transfer member J⁵ is withdrawn, the resilient clip V yielding to disengage from the blank. These operations are illustrated in Figures 9 to 12, inclusive. During the shearing operation the thickness of the shear member will displace the blank in a forward direction and such movement is permitted by reason of the resiliency of the stop U. This is a desirable feature as otherwise the pressure of the blank against a rigid stop might tend to dislodge the same.

50 What I claim as my invention is:

1. In a machine of the character described, the combination with a frame, of reciprocatory means mounted on said frame for periodically advancing the stock, means for reversely feeding the stock a slight amount, and a sizing die through which the stock is advanced during the forward movement of said reciprocatory means, said die having a floating engagement with said frame permitting movement thereof with said stock during the reverse feeding.

2. In a machine of the character described, stock advancing means, a stop gauge adapted to move the stock rearward to obtain an exactly measured length to be sheared, a die for sizing the stock advanced and movable with the stock during rearward movement thereof, and means providing frictional resistance to such rearward movement of the die.

70 3. In a machine of the character described, stock advancing means, a stop gauge adapted to move the stock rearward to obtain an exactly measured length to be sheared, a die for sizing the stock advanced and movable with the stock during rearward movement thereof, and a ten-

sioned shoe providing frictional resistance to such rearward movement of the die.

4. In a machine of the character described, stock advancing means, a stop gauge adapted to move the stock rearward to obtain an exactly measured length to be sheared, a die for sizing the stock advanced and movable with the stock during rearward movement thereof, and means for limiting such rearward movement of the die.

5. In a machine of the character described, stock advancing means, a stop gauge adapted to move the stock rearward to obtain an exactly measured length to be sheared, a die for sizing the stock advanced and movable with the stock during rearward movement thereof, and an adjustable stop for limiting such rearward movement of the die.

6. In a machine of the character described, stock advancing means, a stop gauge adapted to move the stock rearward to obtain an exactly measured length to be sheared, a die for sizing the stock advanced and movable with the stock during rearward movement thereof, a tensioned shoe providing frictional resistance to such rearward movement, and means for varying the tension on said shoe to alter the resistance on said die.

7. In a machine of the character described, a frame through which stock may be advanced, a stop gauge adapted to move the stock rearward to obtain an exactly measured length to be sheared, a die for sizing the stock as it is advanced and movable with the stock during rearward movement thereof, a supporting collar for said die fixed to said frame and permitting the rearward movement of the die, and means extending through the collar providing frictional resistance to such rearward movement of the die.

8. In a machine of the character described, a frame through which stock may be advanced, a stop gauge adapted to move the stock rearward to obtain an exactly measured length to be sheared, a die for sizing the stock as it is advanced and movable with the stock during rearward movement thereof, a supporting collar for said die carried by said frame and permitting the rearward movement of the die, and means for limiting such rearward movement of the die.

9. In a machine of the character described, a frame through which stock may be advanced, a stop gauge adapted to move the stock rearward to obtain an exactly measured length to be sheared, a die for sizing the stock as it is advanced and movable with the stock during rearward movement thereof, a supporting collar for said die carried by said frame and permitting the rearward movement of the die, and an adjustable stop for limiting such rearward movement of the die.

10. In a machine of the character described, a frame through which stock may be advanced, a stop gauge adapted to move the stock rearward to obtain an exactly measured length to be sheared, a die for sizing the stock as it is advanced and movable with the stock during rearward movement thereof, a supporting collar for said die carried by said frame and permitting the rearward movement of the die, and a tensioned shoe extending through said collar providing frictional resistance to such rearward movement of the die.

11. In a machine of the character described, a frame through which stock may be advanced, a stop gauge adapted to move the stock rearward to obtain an exactly measured length to be

- sheared, a die for sizing the stock as it is advanced and movable with the stock during rearward movement thereof, a supporting collar for said die carried by said frame and permitting the rearward movement of the die, a tensioned member extending through said collar providing frictional resistance to such rearward movement of the die, and adjustable means carried by the frame for varying the tension on said shoe.
12. In a machine of the class described, the combination with means for shearing stock and means for advancing the stock toward said shearing means, of means for moving the stock rearward to obtain an exactly measured length to be sheared, and a die for sizing the stock as it is advanced held against movement during advancement of the stock but movable with the stock during rearward movement thereof.
13. In a machine of the class described, the combination with means for shearing stock and means for advancing the stock toward said shearing means, of means for moving the stock rearward to obtain an exactly measured length to be sheared, a die for sizing the stock during advancement thereof, and a mounting for said die holding the same against movement during advancement of the stock but permitting the die to move with the stock during rearward movement thereof.
14. In a machine of the class described, the combination with means for shearing stock and means for advancing the stock toward said shearing means, of means for moving the stock rearward to obtain an exactly measured length to be sheared, a die for sizing the stock as it is advanced held against movement during advancement of the stock but movable with the stock during rearward movement thereof, and means for limiting the movement of the die with the stock.
15. In a machine of the class described, the combination with means for shearing stock and means for advancing the stock toward said shearing means, of means for moving the stock rearward to obtain an exactly measured length to be sheared, a die for sizing the stock as it is advanced held against movement during advancement of the stock but movable with the stock during rearward movement thereof, means providing frictional resistance to movement of the die with the stock, and means for limiting movement of the die with the stock.
16. In a machine of the class described, a frame through which stock may be advanced, means for moving the stock rearward to obtain an exactly measured length to be sheared, a die for sizing the stock as it is advanced and movable with the stock during rearward movement thereof, and a support for said die carried by said frame and permitting the rearward movement of the die.
17. In a machine of the class described, a frame through which stock may be advanced, means for moving the stock rearward to obtain an exactly measured length to be sheared, a die for sizing the stock as it is advanced and movable with the stock during rearward movement thereof, a support for said die carried by said frame and permitting the rearward movement of the die, and means carried by the support providing frictional resistance to such rearward movement of the die.
18. In a machine of the class described, a die for sizing stock, said die being held against movement while the stock is being sized but mov-

able with the stock upon movement thereof in a predetermined direction, means providing frictional resistance to movement of the die with the stock, and means for limiting such movement of the die with said stock.

19. In a machine of the class described, a frame, an annular member fixed to said frame, a sizing die for stock slidable within said annular member, a friction shoe carried by the frame and engaging said die, and means for limiting sliding movement of the die, including an adjustable element carried by the frame in the path of said die.

20. In a machine of the class described, a frame, shearing means for the stock carried by the frame, means carried by the frame for advancing the stock toward the shearing means, means for moving the stock rearward to obtain an exactly measured length to be sheared, a die for sizing the stock as it is advanced held by said frame against movement during advancement of the stock but movable relative to the frame during rearward movement of the stock, and means carried by said frame for limiting the movement aforesaid of said die.

21. In a machine of the class described, a frame through which stock may be advanced, means for moving the stock rearwardly a slight amount relative to the frame, an annular member fixed to said frame and having a recess in a wall thereof, a sizing die for the stock having a floating engagement with said recess permitting movement of the die with the stock during rearward movement thereof, and means for resisting the floating movement of the die including a friction shoe carried by said frame and engaging said die.

22. In a machine of the class described, a die for sizing stock, said die being held against movement while the stock is being sized but movable with the stock upon movement thereof in a predetermined direction, and means providing frictional resistance to movement of the die with the stock.

23. In a machine of the class described, a frame, means mounted on the frame for advancing stock relative to the frame, means for reversely moving the stock a slight amount relative to the frame, and a sizing die for the stock held by the frame against movement with the stock while it is being advanced and having a floating engagement with said frame permitting movement of the die with the stock during reverse movement thereof.

24. In a machine of the class described, a frame, means mounted on the frame for advancing stock relative to the frame, means for reversely moving the stock a slight amount relative to the frame, a sizing die for the stock, and a mounting for the die holding it against movement while the stock is advanced but permitting the die to move with the stock relative to the frame when the stock is reversely moved.

25. In a machine of the class described, a frame, shearing means for the stock carried by the frame, means carried by the frame for advancing the stock toward the shearing means, means for moving the stock rearward to obtain an exactly measured length to be sheared, a die for sizing the stock, and a mounting for said die holding it against movement while the stock is advanced but permitting the die to move with the stock during rearward movement of the stock.

26. In a machine of the class described, a

frame, shearing means for the stock carried by the frame, means carried by the frame for advancing the stock toward the shearing means, means for moving the stock rearward to obtain an exactly measured length to be sheared, a die for sizing the stock, a mounting for said die holding it against movement while the stock is advanced but permitting the die to move with the stock during rearward movement of the stock, 10 and means carried by said frame for limiting the movement aforesaid of said die.

27. In a machine of the class described, a sizing die for stock, means for advancing stock through the die, means for shearing the sized stock, means for reversely moving the stock a slight amount to obtain the desired length to be sheared, and a mounting for the die holding it against movement while the stock is advanced but permitting the die to move with the stock 20 when it is reversely moved.

28. In a machine of the class described, a sizing die for stock, means for advancing stock through the die, means for shearing the sized stock, means for reversely moving the stock a slight amount to obtain the desired length to be sheared, a mounting for the die holding it against movement while the stock is advanced but permitting the die to move with the stock when it is reversely moved, and means for limiting said 30 movement of the die.

29. In a machine of the class described, a sizing die for stock, means for advancing stock through the die, means for shearing the sized stock, means for reversely moving the stock a slight amount to obtain the desired length to be sheared, a mounting for the die holding it against movement while the stock is advanced but permitting the die to move with the stock when it is reversely moved, means resisting said movement 40 of the die, and means for limiting the resisted movement of the die.

30. In a machine of the class described, a siz-

ing die for stock, means for advancing stock through the die, means for reversely moving the stock a slight amount, and a mounting for the die holding it against movement while the stock is advanced but permitting the die to move with the stock when it is reversely moved.

31. In a machine of the class described, a frame, a mounting for a sizing die carried by said frame, a sizing die for stock carried by said mounting, means for advancing stock through the die, and means for reversely moving the stock a slight amount, the die being held by the mounting against movement during advancement of the stock and movable relative to the mounting with the stock when it is reversely moved. 15

32. In a machine of the class described, a sizing die for stock, means for advancing stock through the die, means for reversely moving the stock a slight amount, a mounting for the die holding it against movement while the stock is advanced but permitting the die to move with the stock when it is reversely moved, and means resisting said movement of the die. 20

33. In a machine of the class described, a sizing die for stock, means for advancing stock through the die, means for reversely moving the stock a slight amount, a mounting for the die holding it against movement while the stock is advanced but permitting the die to move with the stock when it is reversely moved, means resisting 30 said movement of the die, and means for limiting the resisted movement of the die.

34. In a machine of the class described, a sizing die for stock, means for advancing stock through the die, means for reversely moving the stock a slight amount, a mounting for the die holding it against movement while the stock is advanced but permitting the die to move with the stock when it is reversely moved, and means for limiting said movement of the die. 40

LEE BERKEBIL.
